United States Patent Office.

IMPROVEMENT IN APPARATUS FOR TYING AND PACKING WOOL FLEECES.

JAMES M. WORCESTER, OF OBERLIN, OHIO.

Letters Patent No. 60,316, dated December 4, 1866.

SPECIFICATION.

TO ALL WHOM IT MAY CONCERN:

Be it known that I, JAMES M. WORCESTER, of Oberlin, in the county of Lorain, and State of Ohio, have invented certain new and useful improvements in Fleece Tying Machines; and I do hereby declare that the following is a full and complete description thereof, reference being had to the accompanying drawings, making a part of this specification, in which—

Figure 1 is a side view of the machine.

Figure 2 is a top view of the same.

Figure 3 is an end view.

Like letters of reference refer to like parts in the different views presented.

This wool table consists of a light wooden frame, A, fig. 1, which is in shape an oblong square, and is supported by the legs, B. These legs are so connected to the frame as to allow of their being turned up within the frame, as indicated by the dotted lines *a*, fig. 2, for the convenience of carrying the table from place to place. C, figs. 1 and 2, are a pair of leaves, which are so connected to the frame by the hinges, *b*, as to permit of their being turned down upon the frame, as indicated by the dotted lines *c*, fig. 2, thereby forming the outer sides of the top of the table. The section of the top between the sides consists of the parallel bars, D. In the three central ones is cut a groove, *d*, to which reference will be made hereafter. E', figs. 2 and 4, are adjustable or sliding heads, which consist of the vertical arms, F, the lower ends of which are tennoned. Said tennons are passed through the spaces between the bars D, and pinned into mortises cut in the cross-piece, G, on the under side of the bars. The shoulders, *f*, rest on the upper side of the bars, and upon which they slide, and are thereby prevented from falling through the position of these heads when in place, as indicated by the dotted lines *h*, fig. 1. H, fig. 2, is a roller over which runs the rope, I, one end of the same being connected to the weight, J, and the other to the adjustable heads above described. These heads are also connected to the roller, K, by means of a rope around which it is wound for the purpose hereafter shown. E', is a crank by which the roller K is turned. M is a curved lever or pawl, the short arm of which is pointed and catches into the holes *i*. As the roller turns, the long arm of this pawl or lever reaches above the top of the frame, as shown in figs. 1 and 3, and the position of which, in relation to the roller and table, is indicated by the dotted lines *j*, fig. 1. N, fig. 2, is a spiral spring, by means of which the pawl is retained in the holes, to be referred to hereafter. O, fig. 3, forms the end of the table, and against the sides of which the leaves C shut and are held, when thus turned up by the spring P, placed across the top of the end piece O, forming thus, together, a box in which the wool is tied in the following manner: The leaves C, above described, are spread out, as indicated by the dotted lines *e*, fig. 2, above referred to. The table is then threaded by passing the strings through the holes *m*, fig. 3, and stretching them along in the grooves *d*, so that the ends of which may reach to the opposite end of the bars. The fleece is then spread out on the table between the heads E, and the sides of which are then folded in until it becomes of the same width of the bar section of the table; the fleece, on being thus folded, the leaves C are then turned up and secured in this position by the spring P, above described. The two heads are then drawn together by the ropes and roller referred to, until they reach the point indicated by the dotted lines *n*, fig. 2, and are there retained by the pawl or lever M. The strings are then lifted from the grooves and brought around the fleece and tied, and when thus tied the leaves are dropped down, one of which, pressing upon the upward projecting arm of the lever, forces the pawl arm from the holes in the roller, and the heads are thereby immediately drawn back to the ends of the table by the weights J, to which they are attached by the rope I. It will be evident from this that the fleece thus done up is pressed together, and not folded or rolled as in the ordinary wool table; hence, it leaves the table in the shape of a small square bale, equally pressed, without being torn or strained apart; and the fleece, however torn or ragged it may have been when laid upon the table, can be tied up neatly and tight, and that, too, with the discolored wool entirely hidden by the flesh side of the fleece.

What I claim as my invention, and desire to secure by Letters Patent, is—

The sliding heads E, weights J, grooved bars D, and the adjustable leaves C, as arranged in combination with the lever M and rollers K and H, in the manner and for the purpose set forth.

JAMES M. WORCESTER.
